UNITED STATES PATENT OFFICE.

NATHAN W. FINCH, OF SPRINGFIELD, ILLINOIS, ASSIGNOR OF ONE-HALF TO STEPHEN A. BRADLEY, OF SPRINGFIELD, ILLINOIS.

ROAD GRADER.

Application filed January 18, 1923. Serial No. 613,450.

To all whom it may concern:

Be it known that I, NATHAN W. FINCH, a citizen of the United States, residing at Springfield, in the county of Sangamon and State of Illinois, have invented a new and useful Road Grader, of which the following is a specification.

This invention relates to road machines, and more particularly to a road machine especially designed for grading road surfaces.

The primary object of the invention is to provide a machine of this character, wherein the scraping blades may be adjusted with respect to each other to properly crown the road surface.

Another object of the invention is to provide means for adjusting the ends of the scraping blades simultaneously, and independently of each other.

20 A still further object of the invention is the provision of means for permitting the blades to be raised to positions in spaced relation with the ground surface over which the machine is moving, thereby permitting 25 the machine to be moved from place to place.

With the foregoing and other objects in view which will appear as the description proceeds, the invention resides in the combination and arrangement of parts and in 30 the details of construction hereinafter described and claimed, it being understood that changes in the precise embodiment of the invention herein disclosed, may be made within the scope of what is claimed, without departing from the spirit of the invention.

35 Referring to the drawings:

Figure 1 is a side elevational view of a road machine constructed in accordance with the present invention.

40 Figure 2 is a plan view thereof.

Figure 3 is a sectional view taken on line 3—3 of Figure 1.

Figure 4 is a sectional view through the blade adjusting carriages and their support.

45 Figure 5 is a sectional view taken on line 5—5 of Figure 1.

Figure 6 is a detail view disclosing one of the cable pulleys.

50 Figure 7 is a detail view of one of the cable pulley supports.

Figure 8 is a detail view disclosing the blade supporting arm employed for adjusting the rear ends of the blade.

55 Referring to the drawings in detail, the frame of the machine includes side rails 5,

which are disposed in proper spaced relation with each other, the forward ends thereof extending downwardly as at 6 where the same have connection with the bar 7 that holds the forward ends of the rails 5 in proper spaced relation with each other. The rear ends of the rails 5 also extend downwardly as indicated at 8, the extremities thereof extending horizontally as at 9 where the same are connected by means of plate 10 providing a platform for the operator of the machine, and at the same time forming a support for the seat 11. At the rear of the machine is an axle 12 on which the rear supporting wheels 13 are mounted, which wheels have sprockets 14 secured thereto, for purposes to be hereinafter more fully described.

The reference character 15 designates the forward truck of the machine, which has pivotal connection with the bar 7 as at 16 so that the machine may be readily guided when hitched to a power device. Secured to the side rails 5 at a point intermediate the ends thereof, is a bracket member 17, the supporting surface of which lies in a plane with the bar 7. This bracket member provides a support for one end of the channel iron 18 that has its forward end secured to the bar 7 as by means of the bolt 19.

Secured to the channel iron 18 is a transversely extending bar 20 provided with openings to accommodate the lower ends of the curved pulley supporting arms 21. Supported above the channel iron 18 is an inverted channel iron 22 that has depending flanges 23 disposed in spaced relation with the flanges of the channel iron 18 to provide guideways between which the sliding carriages 24 move.

Each of these carriages comprises an angle iron 25 that contacts with the inner surfaces of adjacent flanges of the angle irons as clearly shown by Figure 4 of the drawings, the webbed portions 26 of the carriages extending through the spaces between the flanges of the channel iron, where the same have connection with the plates 27 and 28 respectively, the plates being shown as extending beyond the outer edges of the webs 26 where they accommodate the inner ends 29 of the blade supporting bars 30 in a manner to permit of pivotal movement of the bars.

The plate 27 of each carriage has an up-

wardly extending end portion 31 adapted to cooperate with the pivoted locking members 32. These pivoted locking members 32 are supported above the rods 33 that have 5 their forward ends positioned in the bracket member 34, the rear ends thereof, extending through the bracket member 35, the extreme ends of the rods 33 extending upwardly as at 36 providing means for rocking or pivoting the locking members 32, into and out of 10 their active positions.

As shown, these locking members 32 are provided with notches extending throughout the lengths thereof, which notches 15 accommodate the upwardly extended end portions 31 of the carriages to lock the carriages in their adjusted positions.

The supporting bars 30 have their forward ends curved downwardly as at 37 and 20 have connection with the scraping blades 38, as at 39, the connection 39 being such as to permit of pivotal movement of the blades with respect to the supporting arm. The blades have their rear ends pivotally connected to the vertically movable angle bar 40 whereby the outer ends of the scraping blades may be adjusted laterally to vary the 25 distance between the blades at their outer ends, and to regulate the angle at which the 30 blades operate.

Bearing members 41 are secured to the side rails 5 and support the rod 42 to which the arm 43 is connected, the arm 43 extending downwardly and being formed with an 35 opening to receive the rod 44, the ends of the rod 44 extending through the angle iron 40 as clearly shown by Figure 3 of the drawings.

Thus it will be seen that by moving the 40 rod 42, the rear ends of the scraping blades may be adjusted vertically with respect to the ground surface over which they operate. One end of the rod 42 has connection with the lever 45 that operates in proximity to 45 the keeper 46 which has a plurality of openings to accommodate the lever, whereby the lever when positioned in certain openings, will hold the rod 42 and iron connected therewith, in their positions of adjustment. 50 By movement of this lever 45, the rear ends of the scraping blades may be elevated to positions to clear the ground surface and throw the blades out of operation when the machine is moved from place to place.

The upper ends of the arms 21 extend laterally as clearly shown by Figure 2 of the drawings, where they support the pulleys 47 over which the cables 48 move, one end of each cable being secured to the drum 60 49 associated therewith so that movement of the drum will cause the cable to be wound thereon or unwound therefrom. The intermediate portions of the cables operate over the pulleys 50 supported at the forward end 65 of the scrapping blade, while the opposite

ends of the cables are connected with the drums 51 loosely mounted on the shaft 52 that carries sprocket wheels 53 on the outer ends thereof.

Splined on the shaft 52 are clutch members 70 54 that have clutch faces cooperating with the clutch faces 55 carried by the drums 51, the clutch members being controlled by the clutch levers 56 whereby the clutches may be operated to clamp the drums to the shaft 75 to cause the same to wind the cables on the drums to accomplish the adjustment of the blades, towards and away from the frame of the machine.

Chains 57 connect the sprocket wheels 14 80 with the sprockets 53, whereby rotary movement of the wheels 13 is imparted to the shaft 52. If it is desired to move the scraping blades inwardly, the clutches are moved to clutch the drums 51 to the shaft 52 to 85 cause the winding of the cable as described.

The drums 49 are mounted on the forward ends of the rods 58, the rear ends of the rod being supported by means of the bracket member 59. Controlling wheels 60 90 are mounted on the rear ends of the rods 58 and disposed in proximity to the operator's seat 11, whereby the operator may, by rotating the rods 58 wind the cables on the drums 49 to accomplish the adjustment of the 95 scraping blades.

In order that the inner ends of the scraping blades will be held against movement, brace rods 61 are provided, which have their forward ends secured under the channel 100 iron 18, while the opposite ends have connection with the member 40 as at 62.

In the operation of the machine, the machine is positioned on the road surface to be graded whereupon the blades are lowered 105 by operating the lever 45, the drums 49 are now operated to allow the cables to unwind therefrom, while the machine is being moved over the ground surface, to the end that the scraping blades contacting with the road surface are moved outwardly until the cables are taut. It is to be understood that prior to this movement, the locking members 32 are moved out of engagement with the upwardly extended portions 31 of the carriages, and that when the scraping blades have been moved to their proper scraping angles, the locking members 32 are returned to their active positions to hold the scraping blades against movement.

When it is desired to return the blades 38 to their inactive positions, the clutch members 54 are moved to cause a rotation of the shaft 52 to wind the cables on the drums 51 to move the forward ends of the blades 115 inwardly.

The lever 45 is now operated to raise the rear ends of the scraping blades out of contact with the ground surface permitting the machine to be moved from place to place. 120

It might be further stated that when the machine is in operation, the lever 45 may be operated to adjust the rear ends of the scraping blades with respect to the surface over which the machine is moving to cause the blades to operate at various depths.

What is claimed as new is:—

1. In a road scraping machine, a frame, laterally movable scraping blades supported under the frame, supporting bars having connection with the scraping blades, carriages movable on the frame, said carriages having pivotal connection with the supporting bars, each of said carriages having an upwardly extending end portion, pivoted locking members associated with the carriages and having notches, said pivoted locking members adapted to be moved to cause the upwardly extended end portions of the carriages to lie within notches of the locking members to restrict movement of the carriages, and means for permitting lateral movement of the scraping blades.
2. In a road scraping machine, a frame, laterally adjustable blades supported under the frame, cables having connection with the blades, manually controlled drums supported on the frame and on which one of the

ends of the cables are wound, power controlled drums on which the opposite ends of the cables are wound, said drums adapted to be operated to move the blades with respect to the frame, and means for adjusting the rear ends of the blades with respect to the ground surface.

3. In a road scraping machine, a frame, scraping blades supported by the frame and having their rear ends pivotally mounted at the rear of the frame, movable carriages supported by the frame, locking members having notches disposed above the carriages said locking frames having means engaging between the notches to lock the carriages against movement, and means for connecting the carriages and forward ends of the scraping blades to cause a relative movement of the scraping blades when the carriages are moved longitudinally of the frame.

In testimony that I claim the foregoing as my own, I have hereto affixed my signature in the presence of two witnesses.

NATHAN W. FINCH.
